UNITED STATES PATENT OFFICE.

HUGH McAFFEE, OF PITTSBURG, PENNSYLVANIA, ASSIGNOR TO CONSOLIDATED LAMP & GLASS CO., OF CORAOPOLIS, PENNSYLVANIA, A CORPORATION OF WEST VIRGINIA.

DESIGN FOR A SHADE.

41,082.

Specification for Design.

Patented Jan. 10, 1911.

Application filed November 4, 1910. Serial No. 590,766. Term of patent 7 years.

To all whom it may concern:

Be it known that I, HUGH McAFFEE, a citizen of the United States, residing at Pittsburg, in the county of Allegheny and State of Pennsylvania, have invented a new, original, and ornamental Design for Shades, of which the following is a specification, reference being had to the accompanying drawings, forming part thereof, in which—

Figure 1 is a perspective view of the design, and, Fig. 2 an inverted plan view thereof.

This invention relates to a new, original and ornamental design for use in the manufacture and decoration of shades in general, but more particularly for the ornamentation of electric and gas lamp shades and comprises, generally stated, the following characteristic features, reference being had to the drawings and numerals thereon.

The numeral 1 upon the drawings indicates the body of the shade same being of rectangular contour with its corners shaped off as at 2. One end of the shade is finished

by a converging circular neck 3 for attachment to a fixture, while as best shown by Fig. 1, each of the four sides of this shade is correspondingly ornamented by the presence of a border line or marginal frame 4, and is crossed diagonally by bars 5 which combine to form the representation of a lattice or trellis extending from side to side and end to end of the said frame 4. Over the said trellis is the representation of a grape vine 6 from which branch grape leaves 7, 8, 9 and 10; while from the said vine 6 depends a cluster of grapes 11 located in the approximate center of the surface bounded by the border line or frame 4 aforesaid.

I claim:

The ornamental design for a shade, substantially as shown and described.

HUGH McAFFEE.
